DESIGN FOR A TRAY

Lyndon F. Fyles, Rochester, Vt.

Application October 26, 1935, Serial No. 59,232

Term of patent 7 years

To all whom it may concern:

Be it known that I, Lyndon F. Fyles, a citizen of the United States, residing at Rochester, in the county of Windsor and State of Vermont, have invented a new, original, and ornamental Design for Trays, of which the following is a specification, reference being had to the accompanying drawing, forming a part thereof, in which

Fig. 2 is a side view thereof; and
Fig. 3 is an end view thereof.

I claim:

The ornamental design for a tray as shown.
In testimony whereof I affix my signature:

LYNDON F. FYLES.
